WIRE-BOUND BOOK

Frank Stanley Schade, Holyoke, Mass., assignor
to National Blank Book Company, Holyoke,
Mass., a corporation of Massachusetts

Application June 17, 1935, Serial No. 26,940

7 Claims. (Cl. 281—16)

This invention relates to improvements in books of paper pad construction of the type in which a coiled wire is loosely threaded through spaced holes in the binding margin of the paper, 5 and has particular reference to such constructions in which several such wire bound pads are interconnected into one composite book or pad.

In a previous application for patent, Serial No. 4,109, filed January 30, 1935, I have described a 10 composite construction of this type in which the helical wire bindings of the superposed pads were interconnected by wire rods extending through the common space formed by the interfitted wire helices. I have now found that certain advantages can be obtained by eliminating the wire 15 rods and substituting therefor a flexible cord or string which is preferably continuous throughout the successive overlapped helices and which is preferably secured permanently to the outside 20 cover boards in which the sheets are held. In some instances it has been found that the rigidity of a wire rod is detrimental in that it will not permit sufficient separation of the sections to afford complete and ready opening of the composite 25 book. This is particularly noticeable when the several sections of the book or pad are individually provided with relatively stiff covers. It has also been found that the flexible cord or string can be applied to the stack of sections much 30 more rapidly than could a series of wire rods. This leads to various economies of manufacture which will be considered more in detail below. Additional advantages of the invention will appear from the following description and claims.

35 Referring to the drawing—

Fig. 1 shows a composite book constructed in accordance with my invention, the view being taken from the back of the book with the covers open;

40 Fig. 2 shows a detail end view of the book opened at its middle; and

Fig. 3 is a perspective detail showing the way the book may be mounted in a permanent cover.

The drawing shows a construction of composite book in which several sections 10 are each provided with individual wire helices 11 which pass in the known manner through holes in the paper stacks. The problem in the present case is concerned, as was the case in my prior application, with the securing together of the several sections by some means engaging the helices and binding them together with sufficient flexibility to permit the composite book to be opened and closed and to lie flat when opened. Instead of 50 using a plurality of rigid wire rods, individually

securing adjacent helices together, the entire series of helices are in this case laced together by a single flexible strand 12 interlaced back and forth along the lengths of the helices as will be apparent from Fig. 1. The ends of the strand are 5 drawn as tight as may be desired for the particular type of book which is being made, and are preferably anchored in place by being adhesively secured underneath straps 13 stuck to the cover boards 14. These cover boards are provided with 10 holes 15 through which the outermost helices pass, and may if desired be secured to an outside permanent cover 16. If the outside cover be used it is preferable to permit the cover boards to overhang the hinge line of the outer cover 15 enough to permit the holes 15 to clear it, as is shown in Fig. 3. This makes a very free mounting for the wire helices and permits the book to be opened flat.

The construction described permits the use of 20 a large number of sections without materially increasing the bulk of the binding. It will be apparent that the strand 12 can be laced through the interfitting helices by some means such as a needle very rapidly and without the necessity for 25 providing any securing means for preventing individual runs of the strand from coming loose. The sections of the strand passing from one pair of helices to the next will effectively prevent the strand coming loose, and will avoid any 30 danger of endwise movement between the sets of helices, just as well as a bent-over end or other securing means which is necessary on each end of each run where a wire rod is used as in my prior application. It will furthermore be seen 35 that the use of a single strand permits the tightness of the composite structure to be regulated at will by drawing up tighter on the ends of the strand, whereas the use of a plurality of separate rods as in my prior application made it necessary 40 to bend over the two ends of each rod separately with sufficient care to prevent endwise play of the rod without undue tightness. A still further advantage of the flexible strand as against a wire 45 rod is that the strand can flex between the adjacent turns of the helices to present a somewhat serpentine formation, giving a degree of separability possible to the separate helices much greater than would be possible with the more rigid member described in the previous case. One additional feature which this construction possesses is that it provides an automatic equalization of 50 the tension in the several sections, the strand being continuous and therefore responding to an excess of tension in one section by a slight shift- 55

ing in its position. The net result is that the books made with a continuous strand have proved to be more uniform in quality and more flexible in use, and these results are accomplished at a greatly reduced cost.

5 The strand may be made of any desired material sufficiently flexible to be interlaced through the several helices and yet sufficiently strong to stand the flexing and wear to which the strand is subjected. I have found that an ordinary fibrous cord serves the purpose very well. In certain conditions it may be found desirable to use a braided strand or one made of flexible wire, the wire in the latter case being necessarily of a much greater flexibility than where the sections are to be secured together by the former individual rod method. Other modifications in the structure may be made as required by the exigencies of the particular use.

10 20 I claim:

1. A relatively thick pad construction comprising a series of assembled thin pad constructions of the type having its sheets bound by a helically coiled wire threaded through its binding margin, said thin pads being assembled by nesting the binding coils together and lacing them into a composite structure by a flexible strand passing back and forth between each adjacent set of binding coils.

25 30 35 40 2. A relatively thick pad construction comprising a series of assembled thin pad constructions of the type having its sheets bound by a helically coiled wire threaded through its binding margin, said thin pads being assembled by nesting the binding coils together and lacing them into a composite structure by a flexible strand passing back and forth between each adjacent set of binding coils and the ends of the strand being secured in place relatively to the outermost binding coils.

45 50 3. A relatively thick pad construction comprising a series of assembled thin pad constructions of the type having its sheets bound by a helically coiled wire threaded through the binding margin of the individual sheets, and in the case of at least the outermost pads through the binding margin of a cover board, said thin pads being assembled by nesting the binding coils together and lacing them into a composite structure by a flexible strand passing back and forth

between each adjacent set of binding coils and the ends of the strand being secured in place by fastening them to the opposed outermost cover boards.

4. A relatively thick pad construction comprising a series of assembled thin pad constructions of the type having its sheets bound by a helically coiled wire threaded through the binding margin of the individual sheets, and in the case of at least the outermost pads through the binding margin of a cover board, said thin pads being assembled by nesting the binding coils together and lacing them into a composite structure by a flexible strand passing back and forth between each adjacent set of binding coils and the ends of the strand being secured in place by fastening them to the outer surfaces of the outermost cover boards, and an outer cover secured over said cover boards to bind the whole into book-like form and to conceal said ends of the strand. 20

5. An interlocking binding comprising a plurality of spiral coiled bound bundles of sheets having their coils interfitting and bound together by a flexible strand interlaced back and forth between the interfitting parts of the coils in a continuous length and having its ends secured relatively to the outermost of the coils. 25

6. A book binding construction comprising a channel-shaped back portion, two covers hinged thereto, a stiff sheet pasted on the inside face of each cover with its inner edge slightly overhanging the channel of the back portion, a plurality of spiral coiled bound bundles of sheets having their coils interfitting and bound together by a flexible strand interlaced back and forth between the interfitting parts of the coils in a continuous length and having its ends fastened between said covers and said stiff sheets pasted to the covers. 30 35

7. A book binding construction comprising a plurality of spiral coiled bound bundles of sheets 40 having their coils interfitting and bound together by a continuous string interlaced back and forth between the interfitting parts of the coils, cover sheets one at each outer face of the assembled bundles, each end of said string being laid against its adjacent cover sheet and binding strips pasted over said string ends and to the cover sheets to form anchorages for the two string ends. 45
